UNITED STATES PATENT OFFICE.

HARRY A. LEONARD, OF HOPEDALE, MASSACHUSETTS, ASSIGNOR TO DRAPER CORPORATION, OF HOPEDALE, MASSACHUSETTS, A CORPORATION OF MAINE.

SPINNING OR WINDING MACHINE.

1,315,973.

Specification of Letters Patent. Patented Sept. 16, 1919.

Application filed December 13, 1918. Serial No. 266,587.

To all whom it may concern:

Be it known that I, HARRY A. LEONARD, a citizen of the United States, and a resident of Hopedale, county of Worcester, and 5 State of Massachusetts, have invented an Improvement in Spinning or Winding Machines, of which the following description, in connection with the accompanying drawings, is a specification, like characters on the 10 drawings representing like parts.

The invention to be hereinafter described relates to spinning or winding machines for placing windings of yarn on carriers and has more particular reference to the mechanism for controlling the manner in which 15 the yarn shall be wound upon the carriers.

In the prior patents granted to George S. Harris, No. 1,167,167, dated January 4, 1916, and to Charles E. Lovejoy, No. 20 1,167,169, dated January 4, 1916, builder motions were described for laying upon yarn carriers or bobbins a yarn mass in which the preliminary windings were laid upon the carriers or bobbins with relatively 25 short traverse and yet with a quick "get away," certain features being disclosed for giving to the base portion of the bobbin its proper formation to permit the yarn to be readily delivered therefrom when the yarn 30 carrier or bobbin was used in the shuttle of a feeler loom. In these prior patents the flexible connection or chain between the builder motion and yarn guiding means had secured to it a projection which, by 35 contact with the cylindrical surface of the let-off drum or pulley carried by the builder arm would deflect the flexible connection and, as the let-off pulley or drum was rotated, to gradually progress the 40 traverse upward upon the bobbin or yarn carriers, the projection would permit the connection to straighten out. The characteristic of the deflecting means in the Harris and Lovejoy patents had proved to be of 45 great practical importance, but in adapting this characteristic deflecting means for use in certain kinds of spinning and winding machines, such as a "quiller," difficulties have been encountered on account of the 50 small space available between the builder motion and the spindle driving means. An important feature of the present invention, therefore, consists of a flexible connection 55 wherein adjacent portions thereof are so constructed and arranged that the flexible

connection may flex in one direction as it passes around one of the coöperating pulleys or drums, but will be prevented from flexure in the opposite direction as it passes about the other coöperating pulley or drum. 60 In carrying this feature of the invention into effect the flexible connection is preferably formed as a chain, two of the joining links being provided with shim extensions and abutting shoulders, whereby the chain 65 may properly conform to one of the pulleys or drums with which it coöperates and be prevented from conforming with the other pulley or drum with which it coöperates when in contact therewith. 70

Another feature of importance in the adaptation of the present invention to practice, is the provision of a projection or shoulder on the let-off pulley or drum carried by the builder arm which, in conjunction with the flexible connection between the builder motion and the yarn guiding means, effects the desired deflection and straightening of the flexible connection. 75

The above features of the invention and others will be hereinafter described in connection with the accompanying drawings which disclose a good practical form of the invention. 80

In the drawings:

Figure 1 represents in front elevation part of a usual "quiller" frame for winding yarn upon carriers, some of the parts being omitted and others broken away for clearness of illustration; 90

Fig. 2 is a section on the line 2-2 of Fig. 1, showing the action of the builder motion during the period of laying the initial winds upon the filling carriers; 95

Fig. 3 is an enlarged detail showing the flexible connection and the drums or pulleys with which it coöperates, some of the parts being broken away;

Fig. 4 is a view of the flexible connection and coöperating drums or pulleys with the parts in a different position. 100

The supporting frame for the "quiller" may be of any usual or desired character and as herein shown comprises the end frames 1 which are suitably connected by longitudinal members 2 in which are supported for up and down movement the rods 3 to which are secured the usual diagonal frame members 4 between which the guiding wires of the quiller extend in usual man- 110

ner for directing the yarn to the carriers or quills. Any number of the rods 3 may be employed suitable to the size and structural conditions of the frame as will be readily understood, the construction being such that by the up and down movement of the rod 3 and the connected guide frame 4, the yarn to be wound upon the carriers is properly directed thereto as the carriers are rotated.

- 10 One or more of the lifting rods 3 projects downward through its bearing 2 and its lower end is provided with a shoe 5 which rests upon the end of a weighted lever 6 pivoted at 7 to a suitable bracket 8. A 15 weight 9 on the lever 6 normally tends to lift the rods 3 as usual in this class of devices. The lever 6 has the upwardly projecting arm 10 carrying the segment 11 to which is secured one end of the flexible connection 12 20 extending between the segment 11 and a slabbed off pulley 13 mounted to rotate on an axis 14 supported in suitable bearings 15 carried by the bracket 16, the construction being such that rotation of the slabbed off 25 pulley 13 will control the up and down movement of the lifting rods 3 in this general class of machines.

Mounted for rotative movement upon the machine frame are the spindles 17, Fig. 1, 30 of which there may be any suitable number and such spindles are provided with whirls or driving pulleys 18 which are driven by a belt 19 from suitable driving means, such as the tin cylinder or drum 20.

- 35 Pivottally mounted on the machine frame at 21, Fig. 2, is the builder arm 22 carrying a roll 23 which rests upon the periphery of the builder cam 24 mounted on the builder cam shaft 25 and driven from a suitable 40 source of power which, in the present instance of the invention, is shown as a pinion or toothed wheel 26, Fig. 1, the construction being such that as the cam 24 rotates, as usual in this class of machines, the roll 23 45 is caused to follow the periphery of the cam to thereby effect a traverse of the yarn guiding means, as will more fully appear.

Mounted on the builder arm is the let-off drum or pulley 27, Fig. 2, provided with a 50 worm wheel 28 which meshes with a worm 29 on a usual worm shaft 30 carried by the builder arm. The worm shaft 30 carries the ratchet wheel 31 which, by means of the pawl 32 and actuating rod 33, connected to 55 the swinging arm 34, causes the worm to be progressively rotated as the builder arm rises and falls. The construction thus far described is or may be of usual character, such, for instance, as disclosed in the Lovejoy 60 patent previously mentioned, or of any other desired style.

Rising from the supporting brackets 16 heretofore mentioned, are the bearing members 35 on which is mounted the shaft 36 65 having secured thereto a drum or pulley 37

and a bevel gear 38. Operatively engaged with the bevel gear 38 is the bevel gear 39 secured to the shaft 14 on which is supported the slabbed off pulley 13 heretofore described, the construction being such that rotation of the slabbed off pulley 13 is controlled through the pulley or drum 37 by the described motion transmitting connections. 70

Extending between the pulleys or drums 27 and 37 is a flexible connection having adjacent elements thereof constructed and arranged to permit the flexible connection to conform to the surface of the drum or pulley 37 as it winds about such drum or pulley, but to prevent flexure of the flexible connection when the latter is wound about the let-off drum or pulley 27 carried by the builder arm. The let-off drum or pulley 27 is likewise preferably provided with a shoulder to coöperate with the elements of the flexible connection to properly deflect the same, as will more fully appear. The let-off drum or pulley 27, Fig. 4, has secured thereto a shouldered element 41 provided with an incline portion 42, such connection of the 80 shouldered element 41 and the let-off drum or pulley 27 being effected in the present instance of the invention by means of a screw 43. The shouldered element 41 is extended circumferentially of the let-off pulley or 85 drum 27 and is provided with a lug 44 through which is threaded the adjusting pin 45 having secured thereto one end of the flexible connection or chain 46, the other end of the flexible connection or chain 46 being 90 secured to the pulley or drum 37 as by means of a screw pin 47, Figs. 3 and 4, the construction being such that by adjustment of the threaded pin 45 the length of the flexible connection or chain may be adjusted. 95

The flexible connection or chain 46 has the shim extension links 48 and 49 which are pivotally connected by a link 50. The shims of these links have shouldered portions 51 which, when the chain is attempted to be 100 flexed about the let-off drum or pulley 27, come into abutting relation and prevent flexure of the chain or connection at this point. The shouldered member 41 is preferably situated on the let-off drum or pulley 105 27 in position to engage the shim extension links 48 and 49 when the parts are in position for commencing the winding of yarn upon the carriers as best represented by Fig. 2. At this time it will be noted that the 110 shim extension links 48 and 49 are not flexed but become substantially rigid and by reason of the shouldered member 41 on the let-off drum or cylinder 27 cause the flexible connection between the pulleys or drums to be 115 deflected. As the let-off drum is gradually rotated contraclockwise, Fig. 2, the shouldered member 41 will gradually recede from the shim extension links with the result that these links will gradually assume a straight- 120 125 130

line formation between the tangential position occupied by the flexible connection between the drums or pulleys, and as the let-off drum is further rotated to let off the 5 flexible connection, as usual in this class of machines, the shim extension links will engage with the pulley or drum 37 and by flexing about their pivotal union with the connecting link 50, will conform to the contour surface of the pulley or drum 37. Thus 10 without abnormal projection of parts the shim extension links serve to effect substantially the same purpose as is secured by the different organization in the prior Harris 15 and Lovejoy patents.

Another feature of the invention is in the association with the character of flexible connection described of the shouldered member 41 and the disposition of the plane of 20 rotation of the let-off drum and pulley 37 in the same or parallel planes whereby the chain or flexible connection 46 may be uniform throughout with the extension of the 25 shim extension links for causing the described deflecting movements.

Claims:

1. In a machine of the character described, the combination of means for delivering 30 yarn to be wound onto carriers, a builder motion for traversing the yarn delivering means and a flexible connection between the 35 yarn delivering means and builder motion comprising a chain, two of the adjoining links of which have shim extensions adapted to engage and prevent flexure of the chain in one direction and permit flexure in the 40 opposite direction.

2. In a machine of the character described, the combination of means for guiding yarn 45 to be wound onto carriers, a builder motion for traversing the guiding means, a chain between the builder motion and traversing means provided with shim extension links 50 permitting flexibility of the chain in one direction and adapted to engage and prevent flexure of the chain in the opposite direction.

3. In a machine for winding yarn onto 55 receivers, the combination of means for guiding the yarn, a builder motion for traversing the guiding means, a flexible connection and co-operating pulleys between the guiding means and builder motion, adjoining portions of the flexible connections having shouldered extensions permitting flex-

ure of the connection in one direction to conform to one of the pulleys and preventing flexure of the connection in the opposite direction.

4. In a machine of the character described, 60 the combination of a builder motion, and yarn guiding means, motion transmitting devices between the builder motion and yarn guiding means including two pulleys and a flexible connection therebetween, one of said 65 pulleys having a shoulder, and the flexible connection having adjoining portions constructed and arranged to flex as they pass about one of the pulleys and prevent flexure as they pass about the shouldered pulley. 70

5. In a machine of the character described, the combination of a builder motion, and yarn guiding means, motion transmitting devices between the builder motion and yarn guiding means including two pulleys and a 75 flexible connection therebetween, one of said pulleys having a shoulder extending beyond the circumferential contour thereof, and the flexible connection having links provided with shouldered extensions on one side thereof to permit flexure of the links to conform to the contour of one pulley and prevent flexure of the links when passed about the other pulley. 80

6. A builder motion comprising a builder 85 arm, a let-off pulley or drum carried thereby, a flexible connection passed about a portion of said pulley or drum and having a jointed link portion that can be flexed in one direction only, a shoulder carried by 90 said pulley or drum on the builder arm to engage the said link portion on its non-flexing side and deflect the flexible connection and then pass from engagement therewith as the pulley or drum is rotated, and a 95 second pulley or drum about which the flexible connection is passed and to the contour of which the flexible connection conforms.

7. A builder mechanism comprising, in combination, a builder arm, two pulleys one 100 mounted on the builder arm and the other on the machine frame, a flexible connection that passes between the pulleys and has two adjoining links constructed and arranged to flex in one direction as they pass about 105 one of the pulleys and prevent flexure as they pass about the other pulley.

In testimony whereof I have signed my name to this specification.

HARRY A. LEONARD.
